UNITED STATES PATENT OFFICE.

HARVEY L. WHEELER, OF FREMONT, OHIO.

WASHING MACHINE.

Application filed March 28, 1921. Serial No. 456,058.

To all whom it may concern:

Be it known that I, HARVEY L. WHEELER, a citizen of the United States, residing at Fremont, in the county of Sandusky and

5 State of Ohio, have invented new and useful Improvements in Washing Machines, of which the following is a specification.

This invention relates to washing machines and more particularly to a combined 10 washing machine and drier.

An object of this invention is to provide a washing machine designed to permit an operator to complete washing laundry in a relatively short time and with a minimum 15 amount of manual labor.

Another object of this invention is to provide a washing machine wherein the clothes to be cleansed are subject to an upward centrifugal action of water for forcing the 20 water through the clothes to thoroughly cleanse them of all foreign matter,

A further object of this invention is to provide a washing machine as specified which is comparatively simple in construction 25 and one which may be easily assembled and taken apart to permit thorough cleaning of the washing machine as well as one in which both the washing and drying operations may be carried on at one time 30 permitting the washing of one batch of clothes while a previously washed batch is being dried.

Other objects of the invention will appear in the following detailed description and in 35 the accompanying drawings wherein:

Fig. 1 is a side elevation of the improved washing machine partly in section.

Fig. 2 is a horizontal section taken on the line 2—2 of Fig. 1.

40 Fig. 3 is a detailed perspective view of a part of the washing machine mechanism.

Fig. 4 is a detailed perspective of the water agitator of the washing machine.

Fig. 5 is a detailed view taken on the line 45 5—5 of Fig. 4.

Referring more particularly to the drawing the improved washing machine comprises a suitable bench or support 1 upon which sheet metal containers 2 and 3 are mounted 50 which containers may be made of any suitable material such as galvanized iron or copper or the like. The container 2, in which the washing operation takes place, has its central portion upturned or spun to provide a centrally upstanding sleeve 4 through 55 which the operating shaft 5 extends. A sec-

ond sleeve 6 is mounted about the sleeve 4 and in spaced relation thereto and has its upper ends out turned to form an annular flange 7 against which a binding block 8 rests. A threaded stud 9 is threaded into the upper ends of the operating shaft 5 and has an inner nut 10 on its upper end by means of which the block 8 is clamped into engagement with the flange 7. A substantially conical member 12 is attached to the perimeter of the block 8 and has its base attached to the upper surface of the bottom 13 of the rotatable substantially cylindrical clothes container 14. The clothes container 14 has its upper end open as clearly shown in Fig. 1 of the drawing and it is perforated to permit the circulation of water therethrough. The substantially conical member 12 is also perforated as shown at 15 to permit the circulation of water therethrough and it is rotated from the shaft 5 by the block 8 and it, in turn, rotates the clothes container 14. The second substantially conical member 16 is placed within the 70

14 has its upper end open as clearly shown in Fig. 1 of the drawing and it is perforated to permit the circulation of water therethrough. The substantially conical member 12 is also perforated as shown at 15 to permit the circulation of water therethrough and it is rotated from the shaft 5 by the block 8 and it, in turn, rotates the clothes container 14. The second substantially conical member 16 is placed within the 75 clothes container 14 and has its apex secured to the lower end of the sleeve 6. The substantially conical shell or agitator 16 is provided with slits 18 formed therein and the metal of which the conical agitator is formed is rounded in opposite directions as shown at 19 and 20 in Fig. 5 of the drawing to cause agitation and 80 to pick up water during the rotation of the member 16. The shaft 5 has a friction pulley 21 thereon which has surface engagement with a friction cone 22 feathered upon the drive shaft 23. The drive shaft 23 may be driven from any suitable type of motor (not shown) through the drive gear 24. A forked lever 24 is connected to the friction cone 22 and to a shift lever 25 by a link 26 and rod 27. The shift lever 25 is positioned 85 at one side of the pedestal or bench 1 so as to permit efficient operation thereof and by rocking the said lever the cone 22 is moved into or out of driving engagement with the friction pulley 21. The speed at which the shaft 5, and consequently the substantially conical members 12 and 16 and the container 14, is driven may be regulated by shifting the friction pulley 21 longitudinally of the shaft 5, the said pulley being held in adjusted positions by a suitable set screw 28.

A suitable cover 29 is provided for the

receptacle 2, and the drain 30, which preferably has a valve 31 therein, is provided for permitting the draining of water from the receptacle 2.

5 In washing clothes, the necessary amount of water is placed in the receptacle 2 and the clothes to be washed are placed in the container 14 after which the lever 25 is shifted to operatively connect the motor or prime mover with the shaft 5. The rotation of the conical member 16 will cause the out turned portions 19 to pick up and agitate the water or cleansing liquid in the receptacle 2, causing it to swirl upwardly within the 10 conical members 16 and 12 being forced outwardly through the openings or perforations 15 in the conical member 12 in substantially upward and circular paths at a relatively high pressure. The forcing of the water or cleansing liquid through the perforations 15, in the manner specified, will force the water through the clothes in the container 14 thoroughly cleansing them, and the water and foreign matter removed 15 thereby from the clothes will pass out of the perforations in the container 14 into the receptacle 2 where the water will be again picked up by the conical agitator 16 and again forced through the clothes, this operation being repeated until the clothes are 20 thoroughly cleansed. To assist the agitator 16 in effectively picking up the water or cleansing fluid baffle plates 32 are mounted, at diametrically opposed positions, in the 25 receptacle 2, extending vertically therein and having their edges, adjacent the cone 16, in close proximity thereto. The baffle plates 32 also act as an abutment causing a retarding of the centrifugal action of the water in the lower portion of the receptacle 2 permitting the foreign matter therein to settle at the bottom of the receptacle or tub 2 adjacent the baffles from which it may be 30 drained off through the drain 30. It will be seen that the parts of the washing portion of the improved washing machine may be easily 35 disassembled to permit thorough cleaning of this structure.

35 After the clothes are thoroughly cleansed or washed they may be removed from the container 14 and placed in the container 35 of the drier structure of the machine. The container 35 is similar to the container 14 being substantially cylindrical in shape and having its side walls perforated as shown at 40 36 while its upper end is open to permit placing of the clothes therein. It also has a central sleeve 37 upturned at the center of its base through which the operating shaft 38 extends. The upper end of the sleeve 37 is flanged as at 39 and a binding block 40 is mounted thereon, being connected to the shaft by means of a threaded stub 41 and a rectangular portion 42 formed upon the 45 shaft which engages in the central rectangu-

lar opening in the binding block 40. The binding block 8 is also provided with a central rectangular opening which receives therein the reduced rectangular portion 8' of the drive shaft 5. An imperforate sheet 50 metal cone 43 is attached to the binding block 40 and to the upper surface of the bottom 44 of the container 45 and acts as a shed to guide the water upwardly for passage out of the container 35 through the perforations 36 during rotary movement of the container. The shaft 38 has a frictional pulley 45 mounted thereon adapted for co-action with a friction cone 46 for rotating the container 35. The friction cone 46 is feathered upon the upper shaft 23 and is moved into and out of operative engagement with the friction pulley 45 by operation of a lever 47. The lever 47 is connected to a shifting lever 48 which is positioned at one side of the 55 bench or support 1 and is connected to the lever 47 by a link 49 and rod 50. When the clothes to be dried are placed within the container 35 and the same is rotated the centrifugal action of the rotating container and clothes therein throws off the water from the clothes which passes out of the container through the openings 36 and which is guided toward the drain 51 of the receptacle 3 by a substantially conical shed 52. A suitable 60 closure 54 is provided for the receptacle 3.

From the foregoing description taken in connection with the accompanying drawings it will be seen that after the clothes are thoroughly cleansed in the container 14 they may 65 be rinsed either therein or removed therefrom and rinsed and placed in the container 35 or else they may be rinsed after being placed in the container 35 by running clear water upon the clothes in the container 35 during rotation thereof which will cause 70 thorough rinsing action of the clothes and after thoroughly rinsed and the flow of water cut off continued rotation of the container 35 will force the greater portion of the water 75 out of the clothes by centrifugal action and eliminate the need of wringing the clothes or running them through an ordinary wringer.

It is, of course, to be understood that the invention may be constructed in various 80 other manners and the parts associated in different relations and, therefore, I do not desire to be limited in any manner except as set forth in the claims hereunto appended.

Having thus described my invention what 85 I claim is:

1. In a washing machine, a perforated clothes container rotatable in a horizontal plane and provided with a relatively large opening in its bottom, an inverted cone attached to said container about the rim of said opening, said inverted cone provided with a plurality of slits extending longitudinally of its side, the edges of said cone adjacent said slits being bent in opposite di-

rections to pick up and force water into said container.

2. In a washing machine, a perforated clothes container rotatable in a horizontal plane and provided with a relatively large opening in its bottom, a perforated cone within said container and having its base attached to the container about said opening, an inverted cone attached to said container, and provided with a plurality of slits in its side, the portions of said inverted cone adjacent to said slits being bent in opposite directions to pick up and force water through and into said first named cone, and a sleeve connected to and connecting the apices of said cones, a housing encasing said clothes container and cones, means for rotating said clothes container and cones, and speed regulating means for regulating the speed of rotation of said container and cones. 25

10 3. In a washing machine, a rotary perforated clothes container rotatable in a horizontal plane and provided with a relatively large opening in its bottom, a perforated cone within said container and having its base attached to the container about said opening, an inverted cone attached to said container, and provided with a plurality of slits 30

15 in its side, the portions of said inverted cone adjacent to said slits being bent in opposite directions to pick up and force water into and through said first named cone, and a sleeve connected to and connecting the apices of said cones. 35

4. In a washing machine, a rotary perforated clothes container rotatable in a horizontal plane, a perforated cone within said container, an inverted cone attached to said container and provided with a plurality of slits extending longitudinally of its side, 40

20 the edges of said cone adjacent said slits being bent in opposite direction to pick up and force water into and through said first named cone, and means for rotating said container and cones. 45

In testimony whereof I affix my signature.

HARVEY L. WHEELER.
